(57) **CLAIM**

The ornamental design for a thin film printer, as shown and described.

DESCRIPTION

FIG. 1 is a back, left, bottom perspective view of a thin film printer showing my new design;

FIG. 2 is a front, right, top perspective view thereof;

FIG. 3 is a front view thereof;

FIG. 4 is an enlarged left view thereof;

FIG. 5 is an enlarged right view thereof;

FIG. 6 is a back view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 1;

FIG. 11 is an enlarged view of the encircled area 11 of FIG. 1;

FIG. 12 is an enlarged view of the encircled area 12 of FIG. 1;

FIG. 13 is an enlarged view of the encircled area 13 of FIG. 2;

FIG. 14 is an enlarged view of the encircled area 14 of FIG. 2;

FIG. 15 is an enlarged view of the encircled area 15 of FIG. 2;

FIG. 16 is an enlarged view of the encircled area 16 of FIG. 3;

FIG. 17 is an enlarged view of the encircled area 17 of FIG. 3;

FIG. 18 is an enlarged view of the encircled area 18 of FIG. 4;

FIG. 19 is an enlarged view of the encircled area 19 of FIG. 4; and,

FIG. 20 is an enlarged view of the encircled area 20 of FIG. 7.

The short dashed broken lines shown in the drawings depict portions of the thin film printer that form no part of the claimed design. The long dash broken lines represent the bounds of the enlarged views and form no part of the claimed design.

1 Claim, 20 Drawing Sheets
